GLASS CLIPS

Arnold A. Zachman, St. Paul, Minn.

Application July 24, 1952, Serial No. 300,599

9 Claims. (Cl. 189—78)

This invention relates to an improvement in glass clips and deals particularly with a clip of resilient material designed to hold one or more glass panes in a desired relation.

In the construction of green houses and the like, it is common practice to employ glass panes arranged in overlapping relation. The panes are usually supported on an inclined plane and the upper edge of the lowermost pane lies beneath the lower edge of the next adjacent pane. In other words, the glass panels are usually overlapped similarly to shingles so that moisture will not leak therethrough.

An object of the present invention lies in the provision of a clip which is designed to support the glass panes in proper overlapping relationship. These clips are designed to assist the sealing composition in holding the panes in place.

An object of the present invention lies in the provision of a resilient clip which cooperates with a glazing bar of inverted T-shape or of L-shaped form. The glazing bar is provided with an undercut shoulder near its upper extremity running throughout its length. The glass clips are designed to engage the lower edge of the upper pane and the upper edge of the lower pane and to resiliently engage the undercut shoulder so as to firmly hold the panes in position.

An added feature of the present invention lies in the fact that the clip may be constructed to engage the lower edge of the uppermost pane only, if desired. Such a clip prevents the uppermost pane from sliding downwardly and obviously is more necessary than a means for holding the lower pane from sliding upwardly. A clip of this type may be more easily removed in the event of broken glass and has some advantages in certain installations.

These and other objects and novel features of the present invention will be more clearly and fully set forth in the following specification and claims.

In the drawings forming a part of the specification:

Figure 1 is a perspective view of a pair of overlapping glass panes showing my clip used in conjunction therewith.

Figure 2 is a perspective view of the clip illustrated in Figure 1.

Figure 3 is a perspective view similar to Figure 1 showing the modified or simplified form of clip.

Figure 4 is a perspective view of the clip illustrated in Figure 3.

The glass panes employed in many types of green house structures are held in overlapping relation upon glazing bars which extend angularly toward the ridge pole of the green house. Figure 1 illustrates a glazing bar 10 which is of inverted T-shaped formation including a central upright flange 11 and a pair of laterally extending coplanar flanges 12 and 13 at its lower extremity. The upper edge of the vertical flange 11 is provided with an enlargement 14 projecting beyond either side surface of the vertical flange 11 and provided with an undercut

2

shoulder between each side of the enlargement and the flange 11. One such undercut shoulder 15 is visible on the exposed side of the flange 11, while another similar undercut shoulder 16 is provided on the opposite side of the flange.

Two glass panes are illustrated in overlapping relation. The lower pane 17 rests upon the flange 12 and is supported thereby. Putty or some other sealing compound is placed upon the flange 12 beneath the pane 17 so as to form a seal between the flange and the glass. In actual practice the lower edge of the pane 17 overlies and overlaps the upper marginal edge of the next lower pane, not illustrated in the drawings.

Figure 1 illustrates only one side edge of the panes, it being understood that the panes are generally rectangular in form and are supported between two parallel glazing bars. The uppermost pane illustrated is indicated at 19. It will be noted that the lower marginal edge 20 of the upper pane 19 overlaps the upper marginal edge 21 of the lower edge 17. The overlapping of the panes does not provide an air space between the panes and the flanges of the glazing bar in view of the putty beneath the glass.

The clip is indicated in general by the letter A. This clip includes a vertically extending portion 22 which is designed to extend into the undercut shoulder 15 and be resiliently engaged thereby. The portion 22 is bent at 23 to form an inclined portion 24 which in use inclines away from the glazing bar. At its lower end, the inclined portion 24 is bent at 25 to provide a bearing portion 26 which is parallel to the surface of the glass pane 19 and is in surface contact therewith. The bearing portion 26 is provided with a down-turned flange 27 along one edge thereof, the flange 27 being designed to engage against the edge 20 of the upper pane 19.

35 In order that the clip may be formed of a strip of metal of substantially equal width throughout, the bearing portion 26 does not extend the full width of the strip, the flange 27 being formed by striking downwardly a portion of what would otherwise comprise a part of the

40 bearing portion. At the edge of the bearing portion opposite to the bent edge 25, the metal strip is bent downwardly to form a vertical panel 29 which is substantially aligned with and on the same plane as the upper portion 22. The vertical portion 29 connects the bearing portion 26 with a bottom portion 30 which is designed to underlie the lowermost pane 17. A flange 31 is struck upwardly from a side edge of the bottom 30, the flange 31 being designed to extend along the upper edge 21 of the lower panel 17. In order that the clip be made of material of substantially equal width throughout, the flange 31 is struck out of the portion which would otherwise comprise a part of the bottom 30, the bottom 30 thus becoming narrower than most of the remainder of the strip.

55 It will be seen that the striking of the flanges 27 and 31 from the panels to which they are attached serves the double purpose of conserving material and of allowing the overlap between the panes to be maintained at a minimum. The upper inclined portion 24 and top retaining portion 22 of the clip may extend the desired width without necessitating an excessive overlap between the panes.

In applying the clip the bottom 30 is usually inserted beneath the upper edge of the lower pane 17 with the vertical portion 29 extending in substantial surface contact with the glazing bar flange 11. The upper pane 19 may then be moved downwardly until the lower edge 20 thereof engages against the flap 27. This is done while the upper end of the clip is free of the shoulder 15. The inclined portion 24 of the clip is next pressed inwardly, the structure flexing sufficiently to engage the upper edge of the vertical portion 22 in the shoulder 15 under slight tension. The tension is normally sufficient to prevent

movement of the clips longitudinally of the glazing bar. However, in any event the flange 31 which engages the upper edge of the lower pane holds the upper pane from moving downwardly so that the tendency for the clip to move longitudinally is at a minimum. Figure 1 of the drawings shows the clip A as employed on the panes overlying the flange 12. Figure 2 indicates the same clip in reversed form showing the construction as it would be employed on the opposite flange 13.

In Figure 3 of the drawings I disclose a modified form of clip which is indicated in general by the letter C. The clip C is virtually identical with the previously described clip A with the exception of the lower part of the clip A which has been omitted. The clip C includes an upright flange 32 which is connected along a line of bend 33 with an inclined portion 34. The lower end of the inclined portion 34 is connected along the line of bend 35 to the bearing portion 36 designed to rest in surface contact with the pane 19. The bearing portion 36 is provided with a vertical portion 37 extending downwardly in substantially the plane of the vertical portion 32. This flange 37 extends along the marginal side edge of the glass pane 19 in surface contact with the flange 11 of the glazing bar 10.

A portion of the bearing portion 36 is cut away and bent downwardly to provide a shoulder 39. This shoulder extends along the lower edge of the pane 19 to hold the pane from sliding downwardly.

The clip C thus acts to hold the pane 19 in place and due to its resilient engagement with the shoulder 39 it keeps the pane from sliding downwardly. The clip C is not as positive in its action as the clip A, but is desirable for use in some instances. For example if certain of the panes become broken, the clip C may be more readily removed. The clip C is also useful as a replacement unit for the clip A after a pane of glass has been removed.

This application is a continuation in part of my previously filed application for Green House Structure, Serial No. 686,324, filed July 26, 1946.

In accordance with the patent statutes, I have described the principles of construction and operation by my glass clips and while I have endeavored to set forth the best embodiments thereof, I desire to have it understood that these are only illustrative thereof and that obvious changes may be made within the scope of the following claims without departing from the spirit of my invention.

I claim:

1. A glass clip including a bearing panel designed to overlie the corner of a pane of glass, downwardly extending flanges extending along two adjoining edges of the bearing portion to extend at right angles along the edges of the glass adjacent the corner thereof, an upwardly and inwardly inclined portion connected to the bearing portion along a third edge thereof, and an upwardly extending portion at the upper edge of said inclined portion extending in substantial alignment with and substantially on the plane of one of the downwardly extending flanges.

2. The structure described in claim 1 and including a bottom portion connected to the lower edge of one of the downturned flanges.

3. The structure described in claim 1 and including a bottom flange secured to the lower edge of said one of said downturned flanges, and a flange on said bottom extending upwardly from an edge thereof in parallel relation to the other downturned flange of the bearing portion.

4. The structure described in claim 1 and in which the other of said downturned flanges is struck from the body of the bearing portion at a point spaced from the edges of the inclined portion and said one downturned flange,

5. A window structure including a glazing bar including a vertical flange and a lateral flange extending laterally from the vertical flange at a point spaced from the upper edge thereof, a pair of glass panes supported in overlapping relation along one edge by said lateral flange, and a resilient clip for holding said panes in proper overlapped relation, said clip including a bearing portion resting upon the corner of the uppermost pane and including downturned flanges along two edges of the bearing portion to extend along the lower edge of the uppermost glass pane and to extend between the edge of the glass pane and the vertical flange of the glazing bar, the edge of the bearing portion opposite the edge bearing the last named downturned flange having an upwardly inclined portion secured thereto inclining toward the vertical flange of the glazing bar, a vertically extending portion connected to the upper edge of the inclined portion, and a shoulder adjacent the upper edge of the vertical flange of the glazing bar engaging said vertical portion to hold the clip in place.

6. A window structure including a glazing bar having a lateral flange, a vertical flange connected thereto, an enlargement at the upper end of said vertical flange, and a shoulder between said enlargement and said vertical flange, a pair of glass panes having an edge thereof supported by said lateral flange and arranged in overlapping relation, a clip having a bearing portion overlying the upper surface of the uppermost pane of the overlapped pair of panes, downturned flanges along two edges of said bearing portion, said flanges extending along the edges of the uppermost pane adjacent the corner thereof, said bearing portion being bent to provide an upwardly inclined portion which inclines over the bearing portion and toward the vertical flange of the glazing bar, and an upper portion on said upwardly inclined portion engaged against said shoulder.

7. The structure described in claim 6 and in which the shoulder is undercut.

8. The structure described in claim 6 and in which one of said downturned flanges is bent to provide a bottom portion, said bottom portion underlying the lowermost pane of said overlapped panes and including an upturned flange engaging the edge of the lowermost pane.

9. A glass clip for holding one or more panes of glass aligned against a glazing bar flange having an angularly positioned adjoining flange provided with an undercut shoulder, said clip comprising a strip of metal of substantially equal width throughout, having a bearing portion, a downwardly turned vertical flange portion adapted to lie between a glass edge and the adjoining flange of a glazing bar, an upwardly and inwardly bent edge of the bearing portion opposite to said downwardly turned flange portion, an inclined portion extending over said bearing portion upwardly and inwardly from said bent edge, and a vertically upwardly extending flange portion substantially aligned on the same plane as the said downwardly turned flanged portion whereby in positioning said glass clip to mount a glass pane on said glazing bar the said downwardly turned flange portion engages against the side edge of a glass pane and said inclined portion is flexed inwardly towards said bearing portion to substantially align said upwardly extending flange under the shoulder on the glazing bar in substantially parallel opposing relationship to said downwardly turned flange portion.
